Closman P. Stocker

Application October 26, 1939, Serial No. 301,469

19 Claims. (Cl. 172—281)

This invention relates to static frequency changers and more particularly to static frequency changers which depend for their operation upon the saturation of magnetic core materials. Specifically my invention has for its purpose the generation of a plurality of frequencies which may be used for signaling purposes in telephone or other electrical systems.

It is an object of this invention to produce without any moving parts two or more signaling tones which are easily distinguishable from each other.

Another object of my invention is to provide a tone signaling device capable of operating over wide variations of input voltage.

It is another object of my invention to generate even harmonics of the input frequency without the use of permanent magnets or direct current.

Another object of my invention is the provision of a magnetic harmonic generator having a closed self-exciting circuit.

Another object of my invention is the provision of a magnetic harmonic generator self-excited by alternating current.

Another object of my invention is to provide a harmonic generator for producing even harmonics when self-excited by alternating current.

Another object of my invention is to produce harmonics in the output wave generated by a frequency changer.

A further object of my invention is to produce even harmonics in the output wave generated by a frequency changer.

Another object of my invention is to double a frequency and produce harmonics of the doubled frequency.

It is another object of my invention to obtain in the output of a frequency multiplier the desired frequency with substantially all of the frequencies lower than the desired frequency eliminated.

It is another object of my invention to generate simultaneously a frequency with a modulated wave and a frequency with an unmodulated wave from a frequency changer which depends upon magnetic saturation for operation.

It is another object of my invention to provide improved stabilizing means for a static type frequency changer.

Another object of my invention is to produce in a frequency changer, harmonics of the output frequency and to accentuate one or more of these harmonics.

It is a further object of my invention to improve the output voltage regulation from a fre-

quency changer by the use of an inductance with a saturable core in the output circuit.

Another object of my invention is to provide a frequency changer in which the generation of the new frequency is substantially unaffected by variations in load.

It is another object of my invention to produce in a frequency changer, a frequency with a modulated wave and a frequency with an unmodulated wave each of which is substantially free and independent of the load variations on the other.

It is another object of my invention to produce in a frequency changer, two different output frequencies, one of which is a modulated wave and the other an unmodulated wave.

Other objects and a fuller understanding of my invention may be had by referring to the following description and claims, taken in conjunction with the accompanying drawings, in which like parts are designated by like reference characters, and in which:

Figure 1 shows a static type frequency changer which is equipped with an output circuit adapted to furnish a tone suitable for signaling purposes and capable of producing even harmonics of the input frequency.

Figure 2 shows a simple output network adapted to be connected to the secondary of the frequency changer to aid in self-excitation and to increase the harmonic content of the output voltage.

Figure 3 comprises the joining of the subject matters of Figures 1 and 2.

Figure 4 shows a rectifier in the output network which introduces even harmonics in the output voltage and because of its non-linear characteristic also adds stability to the circuit operation, and

Figure 5 shows the preferred embodiment of my invention when using a common magnetic core in the main part of the frequency changer and using the transformer method of insuring stable circuit operation.

My invention relates to a static type frequency changer and in the present application I will describe it as being designed to operate in conjunction with the automatic switching apparatus in dial type telephone offices but my invention may find utility in operation with other electrical systems. As is well known to those skilled in the art, the dial type telephone utilizes tones for signaling purposes. For instance, dial tone indicates to a user that the telephone is ready for use, and an interrupted tone is often

used to indicate a busy line condition. There are many other uses for tone in the automatic telephone systems, but at the present time, all necessary functions can be performed by two different tones.

At present, these tones are generated by rotating equipment for the large offices or by vibrating contact equipment for the small dial offices. In either case these units are adapted to operate from battery and furnish high tone and low tone. Such tone generators are subject to maintenance difficulties. Particularly, with the vibrating contact type of tone generating equipment there is the problem of eliminating radio interference, preventing noise from entering the talking battery, and maintaining contact adjustment.

It is customary to use frequencies of the order of 500 cycles per second for the high tone and frequencies between 120 and 180 cycles per second for the low tone. However, in order to make the low tone transmit well over the telephone circuits, it is necessary to provide ample components of frequencies higher than 120 and 180 cycles in the tone. From a study of the art of static frequency changers one might be inclined to conclude that suitable frequencies might be obtained from prior types of static frequency changers for use as high and low tones in telephone signaling systems. However, from a practical standpoint there have been numerous difficulties to retard the adoption of any such prior schemes.

For example, in order to obtain suitable tones from the old type of static frequency changers elaborate filter circuits were required in order to obtain a good clear note which would transmit well. It was also difficult to obtain tones from the static type frequency changer which sounded like the tones in use in the telephone industry. In addition the increased cost of the old static equipment over the cost of the vibrating type equipment further retarded its adoption. By means of my invention I am able to make a simple static type tone generator which almost exactly duplicates the tones derived from former tone generating systems and is inexpensive enough because of the elimination of complicated filters and other equipment, to compare favorably with the most inexpensive apparatus available today. Furthermore, in my device there are no adjustments, no contacts to maintain, and the device positively cannot produce radio interference or introduce noise into the talking battery.

With reference to Figure 1, I show transformers 11 and 12 having primary windings 13 and 14 connected in series with each other, with capacitor 22 and with a source of alternating current 10, forming a ferro-resonant circuit. Secondary windings 15 and 16 are connected so that practically no voltage of the frequency of source 10 appears across the terminals 25 and 26 when the circuit to condenser 17 is open. A circuit arrangement as shown in Figure 1 has a tendency to generate even harmonics of the frequency of source 10 and this tendency can be greatly enhanced by tuning the circuit to an even harmonic of source 10 by a suitable capacitor 17 and linear inductance 35.

With capacitor 17 and linear inductance 35 connected to secondary windings 15 and 16 a closed self-exciting circuit is established and a current of a harmonic frequency flows therein and self-excites the saturable magnetic paths

of the transformers 11 and 12 to produce an increased transfer of energy from the primary windings to the secondary windings. When the circuit is properly adjusted this self-exciting action is cumulative and the current builds up until it reaches an operating value. Such a circuit may be characterized as a closed self-exciting circuit. The terms "closed self-exciting circuit," "self-exciting circuit" or "self-exciting alternating current circuit means," as used in this application refer to a frequency changing circuit in which the conversion of energy to the new frequency from the supplied frequency is accomplished through the effects on the saturable magnetic paths of the flow of current of the new frequency. In my invention the flow of alternating current in the self-exciting circuit produces instantaneous differences between the degrees of magnetization of the two saturable magnetic paths, and it is this difference of magnetization which makes possible the transfer of energy from the source 10 to the self-exciting circuit. In the self-excited circuit, the self-excitation of the saturable magnetic paths results from a leading current flowing through a capacitor. The cooperation of self-excited circuit and the ferro-resonant circuit is a distinguishing feature of my invention. Under an operating condition many harmonics of source 10 other than the frequency tuned by capacitor 17 and linear inductance 35, are present in the circuit. It is therefore possible to obtain a low tone directly from the secondary circuit. Taps 23 and 24 may be used for this purpose, or separate windings could be used. However, when load is taken directly from the secondary windings it has a detuning effect and under some load conditions the circuit becomes inoperative.

In order to avoid this detuning effect, I prefer to obtain the current for producing the low tone from a low tone output circuit comprising a transformer 18, and a capacitor 21 connected in series with the primary winding 19 of the transformer 18. The load is supplied from the secondary winding 20 of transformer 18.

From test observations, I find that a distinctive low tone is obtained by energizing the low tone output circuit with voltage from either of the primary windings 13 and 14 of the transformers 11 and 12 or with voltage mostly from either one of the two primary windings. In Figure 1, the low tone output circuit is connected across the primary winding 14 of the transformer 12, but may be connected across the primary winding 13 of the transformer 11. The low tone output circuit may also be energized with voltage from either of the secondary windings 15 and 16 or with voltage mostly from either one of the two secondary windings.

The low tone supplied by the low tone output circuit is made up of a number of frequencies. The capacitor 21 and the transformer 18 are so proportioned that the low tone output circuit is resonant to a frequency higher than the frequency of source 10. In the case where the tone generator is used with telephone equipment this resonant frequency would be in the neighborhood of 600 cycles or higher.

A desirable feature of my low tone output circuit is that a load on output winding 20 can never stop the flow of low frequency current flowing through windings 15 and 16 because at this low frequency the impedance of capacitor 21 is made large compared with the impedance of winding 19. With this construction, load on

winding 20 does not appreciably affect the remainder of the frequency changer.

It should be pointed out that either or both of transformers 11 and 12 may be auto-transformers, and in particular, when the ratio of transformation is one to one, one of the transformers may be a simple choke and the other a center tapped transformer.

The use of capacitor 22 makes it possible to operate transformers 11 and 12 at saturation and to maintain a saturated condition over wide variations of the voltage of source 10. To obtain this result I adjust the primary circuit including capacitor 22 and windings 13 and 14 to jump into ferro-resonance. Capacitor 22 also causes the circuit to generate a higher percentage of harmonics. This improvement in harmonic output is apparently a result of the increase of harmonics in the input current caused by the introduction of capacitor 22. I have found that the optimum value of capacitor 17 depends upon the value of capacitor 22 for a given setup and in the samples tested the harmonics generated were increased by simultaneously increasing capacitors 17 and 22 as long as ferro-resonance was maintained in the input circuit.

It is possible to use a substantially linear inductance instead of capacitor 22 in the input, but in this case it is desirable, although not absolutely necessary, to connect a capacitor directly across the windings 13 and 14 to maintain a condition of parallel ferro-resonance. Such an arrangement has been found to operate satisfactorily and can also be applied to Figures 3, 4 and 5.

The frequency changer can be made to operate without the use of linear inductance 35, but the harmonic content of the output voltage on winding 20 is reduced by removing this inductance, and the circuit becomes less stable in its operation. The inductance 35 seems to cause a more pronounced modulation to take place in the low tone circuit consisting of capacitor 21 and winding 19 on transformer 18. This is probably due to the fact that there are more harmonics in the voltage induced in winding 14 on transformer 12 when inductance 35 is used as compared with the operation of the circuit when this is omitted.

The description up to the present point shows how I may obtain a low tone from my static frequency changer. I shall now explain how to obtain a high tone from the same frequency changer.

To obtain a supply of high tone from my frequency changer I have developed a simple output network of the type shown in Figures 2 and 3.

The terminals 27 and 28 of Figure 2 may be connected to the terminals 25 and 26, or to taps indicated generally by the reference characters 23 and 24. When connected to the terminals 25 and 26 the Figure 3 is evolved. In the high tone output network, capacitors 29 and 30 and inductance 31 are adjusted so that the predominant frequency component of the current flowing through primary winding 33 of output transformer 32 is the desired frequency. Although I refer to Figure 2 as a simple output network, the circuit cooperates with the main frequency changing circuit to produce a new and improved result.

According to my invention, I take advantage of the fact that the impedance looking into terminals 25 and 26 of transformers 11 and 12

to which the high tone load circuit may be connected, includes a negative resistance characteristic under certain operating conditions. This characteristic depends upon capacitor 17 and when the circuit of Figure 2 is connected to terminals 25 and 26 the negative resistance characteristic also depends upon the magnitude and phase angle of the current into the output network.

In this combined circuit the impedances may be so adjusted that the current of the desired frequency is large in comparison with the current of undesired frequencies.

The capacitor 30 serves to increase the current flow through inductance 31. In a given setup in which source 10 supplied 60 cycles, I have obtained a current flow of 250 milliamperes, 240 cycles through capacitor 29 and inductance 31 with capacitor 30 omitted. By the addition of capacitor 30 and readjustment of inductance 31, the current flow through inductance 31 was increased to almost 500 milliamperes, although the current through capacitor 29 was maintained at approximately 250 milliamperes.

According to my invention it is possible either to obtain an abundance of harmonics in the high tone output or to obtain an approximately sinusoidal output voltage. If the harmonics are desired I prefer to operate the core of transformer 32 at or near saturation which also tends to maintain the output voltage within narrower limits. When the more nearly sinusoidal output voltage is desired transformer 32 should be made approximately linear. Also, I prefer to have the impedance of the primary winding 33 low compared with the impedance of inductance 31. It is to be understood that inductance 31 is approximately linear. Under this condition the current passing through these windings is nearly sinusoidal, and when the core of transformer 32 is saturated, the output voltage across secondary winding 34 contains considerable harmonics. It is possible to place primary winding 33 in series with capacitor 30 instead of in series with inductance 31, but under this condition, even though the impedance of winding 33 may be small compared with the impedance of capacitor 30, a distortion of current wave shape occurs which reduces the harmonic content of the voltage across secondary winding 34. If a more nearly sinusoidal output wave shape is desired, it can be obtained by making high tone transformer 32 more nearly linear as was previously mentioned, and in this case primary winding 33 may be placed in series with either inductance 31 or capacitor 30.

By making the impedance of primary winding 33 low compared with the impedance of tuning inductance 31, I am able to prevent variations in load from disturbing the tuning of the output network.

In general the output network shown in Figures 2 and 3 acts as a high-pass filter in addition to its function of aiding in the generation of the desired frequency. However, it will be recognized that output transformer 32 being in series with inductance 31 does not constitute the normal type of high-pass filter circuit.

The inductance 35 makes it possible to tune capacitor 17 much more closely with windings 15 and 16 and also stabilizes the operation of the entire circuit. The stabilizing action of inductance 35 increases the operating range of the frequency changer. Under tests the frequency

changer operated satisfactorily over a maximum range of 103 to 127 volts without stabilizing inductance 35. By the addition of stabilizing inductance 35 the frequency changer operated satisfactorily over input voltage ranges from 80 volts to 140 volts. Although the exact theory explaining the operation of stabilizing inductance 35 may be subject to debate, one theory for its effective action is that it tends to prevent the flow of the higher harmonics through capacitor 17 and to force these higher harmonics through capacitors 29 and 30, although I do not intend to be bound to this theory. In effect, inductance 35 seems to function to separate the frequencies flowing through capacitor 17 and the frequencies flowing through capacitors 29 and 30. Although I have shown inductance 35 in series with capacitor 17 only in Figures 1 and 3, it is to be understood that it may be added to Figure 4. As explained with reference to Figure 1, inductance 35 also improves the low tone from output winding 20.

By supplying 60 cycles from source 10 in Figure 3, it is possible to obtain 480 cycles from output winding 34. This frequency is suitable for use as high tone in the telephone systems. However, the amount of power available from winding 34 is comparatively small with respect to the power input and what is more important the tone generated does not sound like the tone obtained from vibrating tone generating equipment. It is believed that this difference in sound is due to the fact that the tone obtained from winding 34 does not contain enough even harmonics of the output frequency. Therefore to make the timbre of the high tone obtained from the static type tone generator comparable to the tone generated by the vibrating type equipment, I have modified Figure 3 and developed the circuit shown in Figure 4.

Figure 4 differs from the previous figures by the addition of rectifier bridge 36 in series with tuning inductance 31 of the output network. The addition of rectifier 36 to the output network including inductance 31 performs two functions, first it introduces even harmonics into the load circuit, and secondly, because of the non-linear characteristic of the rectifier, the stability of the entire circuit is improved. I have found that if an adjustable resistor is substituted for rectifiers 36 that stable operation of the frequency changer circuit can be maintained if the value of the resistor is increased as the input voltage from source 10 is decreased. As is well known, the impedance of the dry disc type of rectifier decreases as the voltage impressed upon the rectifier is increased. In the preferred operating range the current flow through inductance 31 and consequently through rectifiers 36 is reduced as the input voltage is decreased. Since a decrease in current flow through rectifiers 36 causes the resistance of rectifiers 36 to increase this change in resistance is in the proper direction to maintain stable circuit operation.

In order to deliver to the load a 480-cycle wave the output network is altered to cause a predominantly 240-cycle current to flow through tuning inductance 31 and rectifiers 36.

Rectifiers 36 are so arranged that they act as a full wave rectifier and therefore double the supplied frequency. Because of this characteristic of a full wave rectifier 480 cycles is supplied to the load connected to the high tone output terminals 37 and 38. Because of the non-linear

characteristics of rectifiers 36, a high percentage of even harmonics of the 480-cycle wave is introduced into the high tone output voltage delivered to the load. The tone obtained from such a device is very similar to the tone delivered from present day vibrating equipment operated from a battery source. With this circuit, however, variations of load have an effect on the tuning of the frequency changer. In particular, it is essential that the load should not constitute an open circuit to the direct current from the rectifier bridge, because if it does the circuit will be detuned by the impedance of the rectifier bridge.

To overcome the disadvantages of the circuit of Figure 4, I prefer to make use of the arrangement shown in Figure 5, which is that of a complete tone generator utilizing a common core transformer type of construction and capable of supplying high and low tone. The primary winding 40 of the high tone output transformer 39 is permanently connected to the rectifier bridge 36, providing a path for the direct current. Furthermore, the D. C. resistance of this path is independent of load conditions on the secondary winding 41. The arrangement shown in Figure 4 is particularly well adapted to furnish tone to a constant load, but when used with a variable load it is desirable to provide rectifiers capable of withstanding the voltage of an open circuit condition.

The rectifiers in the circuit of Figure 5 however, need to sustain only a small voltage, the value of which is determined by the resistance and impedance of winding 40. This arrangement makes possible to obtain a low tone voltage across winding 20 which is independent of the load condition of the high tone output circuit.

A further advantage of the arrangement of Figure 5 over that of Figure 4 arises from the fact that when the impedance of transformer 39 is properly proportioned, the presence of any frequencies lower than the desired frequency is minimized in the output.

I prefer to operate the core of transformer 39 at saturation to increase the harmonics in the output. The normal current wave shape from a rectifier bridge is characterized by a rapid rate of change of current when the current is low. By making transformer 39 saturated, I take advantage of this characteristic of the rectifiers. The impedance of winding 40 is small when the current magnitude is large, and its impedance is high when the current magnitude is small. Therefore, the rapid rate of change of current occurs at a time when the transformer is best suited to transmit a peaked voltage to the secondary. This peaked voltage is highly desirable in duplicating the tone produced by present vibrating equipment, and at the same time, the high harmonics present in the peaked voltage transmit well through telephone circuits.

Capacitor 42 across the primary winding 40 is proportioned so that a local anti-resonant circuit is formed, the anti-resonance frequency being of the order of some of the desired harmonics of the output frequency. The magnitude of these harmonics is therefore increased by the addition of capacitor 42.

The circuit shown in Figure 5 is the preferred form of my invention using a common core type of construction, and includes a new method of obtaining stable circuit operation by means of stabilizing auto-transformer 54 which will be described as the circuit is explained.

In Figure 5, the current from source 10 passes

through capacitor 22 and windings 44 and 45 magnetizing core 43 to a sufficient degree to make its operating characteristic non-linear. The windings are arranged so that when there is no current through winding 47 there is practically no magneto-motive force developed from windings 44 and 45 across the portion of core 43 included by winding 47.

With capacitor 17 connected across at least a portion of winding 47 a current flows through winding 47 and capacitor 17. The flux induced by this current flow through winding 47 is superimposed on the flux already present in the core to cause changes in reluctance through the effect of the non-linear magnetization characteristic of core 43. These changes in reluctance produce additional coupling between winding 47 and windings 44 and 45, the coupling being a function of the current through winding 47. In operation the voltage induced in winding 47 depends upon that mutual impedance or coupling and the value of the capacitors 17, 28 and 30 and impedance of winding 55 of stabilizing transformer 54 connected to winding 47. If the proper phase angle exists between the current and voltage in winding 47, oscillations in the circuit including winding 47 will have a frequency which is a harmonic of the frequency of source 10. Furthermore, these oscillations are self-starting and self-sustaining.

I have found that stability of circuit operation can be maintained over wide variations of input voltage if the two oscillating circuits, one including condenser 17 being the self-excitation circuit and the other including the rectifiers 36 being the high tone output network, are coupled as shown in Figure 5. Winding 55 on stabilizing transformer 54 is in the output oscillating circuit and winding 56 is in series with capacitor 17 in the self-excitation circuit. In effect, winding 55 is used for tuning purposes and winding 56 is used for stabilization. The exact manner in which winding 56 stabilizes the circuit may be subject to debate, but I have found that reversing the phase of winding 56 with respect to winding 55 causes the circuit to become unstable. If winding 55 is used for tuning purposes and stabilizing winding 56 is omitted, the circuit is operative only over a very narrow range of input voltages with approximately the same high tone output as when the stabilizing winding 56 is used, or if the maximum output is reduced the circuit may be made to operate over a somewhat wider range of input voltage.

In a particular case, the stabilizing winding constituted approximately 8% of the total winding on transformer 54. By thus coupling the two oscillating circuits together, I have maintained stable circuit operation when the input voltage varied between 70 volts and 220 volts. When the input voltage was varied over a slightly narrower range, between 100 volts and 210 volts, the current flowing through winding 55 and therefore through rectifiers 36 was maintained within limits of plus or minus 5%. With this high degree of stabilization the high tone output was practically constant over this range.

It is well to point out that either even or odd harmonics may be obtained from winding 47 on the core 43. By supplying 60 cycles from source 10 to a circuit as shown in Figure 5, I have changed the predominant frequency flowing through condenser 17 and winding 47 from 120 cycles to 180 cycles merely by changing the tuning. With a frequency of 120 cycles flowing

through winding 47, I obtain a low tone from output winding 20 which is a harmonic of 60 cycles modulated at 120 cycles. However, under certain conditions it is possible to make the 60-cycle component across winding 45 modulate the higher frequency and obtain a harmonic of 60 cycles from output winding 20 which is modulated at 60 cycles. It is therefore to be understood that the modulating frequency may be controlled, and the quality of the low tone obtained from output winding 20 altered accordingly.

Capacitor 17 serves to maintain the proper phase angle in the self-exciting circuit to sustain oscillations of a frequency which is a harmonic of the frequency of source 10.

Capacitors 29 and 30 and linear inductance 31 constitute the output network which, for example, may be so tuned that the combination of the two circuits sustains oscillations of the 4th harmonic of the frequency of source 10. Some harmonic other than the fourth might be selected, but in this particular case, 480 cycles, which is the eighth harmonic of the frequency of source 10 is desired at the output of the rectifiers and for this reason the network is tuned to pass 240-cycle current through rectifiers 36. Capacitor 17 is so selected as to pass predominantly second harmonic current and the presence of this second harmonic current improves the quality and quantity of the 4th harmonic current. In addition to the self-excitation previously mentioned in this description and depending upon the phase relation between the 2nd and 4th harmonic currents, the action of each current upon the saturation of the core 43 is such that it produces a voltage to reinforce the other current.

The actual values of harmonics selected above apply only to a given case and other harmonic voltages may be obtained by properly selecting the values of the capacitors and inductances used. When the frequency changer is used to provide signal tone in telephone systems the harmonics in the output wave serve both to improve the transmission characteristic of the signal and to improve the quality of the tone.

It is possible to obtain an 8th harmonic output wave by placing the rectifier bridge in series with capacitor 30 instead of in series with winding 55 of stabilizing transformer 54 but in this case the high tone output wave contains fewer high harmonic frequencies than when the circuit of Figures 4 and 5 are followed, because the capacitors 17, 28 and 30 effectively short circuit the higher frequencies. However, when the impedance of winding 55 is in series with the output this high frequency appears in the output wave.

As previously mentioned capacitor 22 is so selected that the input circuit including windings 44 and 45 operates in series ferro-resonance from source 10. Changes in input voltage therefore have little effect on the voltage across windings 44 and 45. The tone generator being stabilized in operation by transformer 54, is capable of delivering an almost constant high tone output for a given load as the input voltage varies over a wide range. With the circuit shown in Figure 5 properly tuned, capacitor 22 aids in assuring that the oscillations through winding 47 are self-starting as well as self-sustaining.

In Figure 5, switch 58 is used to connect the circuit with source 10, and fuse 59 is proportioned to operate in case the circuit draws an excessive current. Resistor 57 is used to discharge capac-

itor 22 when switch 58 is opened or fuse 59 operates.

It should be pointed out that in operation, a voltage may develop between the output network and ground due to an electrostatic field. While I have not shown the method of reducing this voltage I prefer to connect one point of the output network to ground through a high resistance. A 250,000 ohm resistor connected between a terminal on rectifier 36, as shown in Figure 5, and the metal cabinet has been found to reduce this potential to a satisfactory value.

Although I have described my invention with a certain degree of particularity, it is understood that the present disclosure has been made only by way of example, and that numerous changes in the details of construction on the combinations and arrangement of parts may be resorted to without departing from the spirit and scope of the invention as hereinafter claimed.

I claim as my invention:

1. A magnetic frequency changer adapted to be energized by a suitable source of alternating current comprising, in combination, magnetic core means having two saturable magnetic paths substantially equal in magnetic characteristics, first winding means for magnetizing said two saturable magnetic paths to substantially the same flux density, second winding means embracing the two saturable paths, said first and second winding means being connected to induce substantially zero voltage of the frequency of the source of alternating currents in the second winding means, a plurality of tuned circuits connected to said second winding means, said plurality of tuned circuits receiving energy from harmonics of the current flowing in said first winding means, and output means connected to and receiving energy from at least one of said plurality of tuned circuits.

2. A magnetic frequency changer adapted to be energized by a suitable source of alternating current comprising, in combination, magnetic core means having two saturable magnetic paths substantially equal in magnetic characteristics, first winding means for magnetizing said two saturable magnetic paths to substantially the same flux density, second winding means embracing the two saturable paths, said first and second winding means being connected to induce substantially zero voltage of the frequency of the source of alternating currents in the second winding means, a plurality of tuned circuits connected to said second winding means, said plurality of tuned circuits receiving energy from harmonics of the current flowing in said first winding means, output means connected to and receiving energy from at least one of said plurality of tuned circuits, and second output means connected to and receiving energy from the first winding means.

3. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, said first and second winding means being connected to induce substantially zero voltage of the frequency of the source of alternating currents in the second winding means, and a self-exciting circuit including a capacitor connected to the secondary winding means to re-

ceive energy therefrom and establishing a leading current of a harmonic of the source to flow through the second winding means to self excite and bias the magnetic core means for generating the new frequency.

4. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, said first and second winding means being connected to induce substantially zero voltage of the frequency of the source of alternating currents in the second winding means, a self-exciting circuit including a capacitor connected to the secondary winding means to receive energy therefrom and establishing a leading current of a harmonic of the source to flow through the secondary winding means to self excite and bias the magnetic core means for generating the new frequency, and output winding means and a capacitor forming a tuned circuit connected in circuit relation with a portion of the first winding means to supply a complex output wave having components including the frequency of the source of alternating current and the new frequency.

5. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, said first and second winding means being connected to induce substantially zero voltage of the frequency of the source of alternating currents in the second winding means, a self-exciting circuit including a capacitor connected to the secondary winding means to receive energy therefrom and establishing a leading current of a harmonic of the source to flow through the second winding means to self excite and bias the magnetic core means for generating the new frequency, output winding means and a capacitor forming a tuned circuit connected in circuit relation with a portion of the first winding means to supply a complex output wave having components including the frequency of the source of alternating current and the new frequency, and an impedance element in series with the capacitor and the second winding means to form a substantially tuned self-exciting circuit.

6. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, one of said winding means having at least two opposed operating windings, a first circuit including a first capacitor and a first inductance element connected in series with each other and in closed circuit relation with the second winding means, a sec-

ond circuit including a second capacitor, a second inductance element and an output impedance element connected in series with each other and in closed circuit relation with the second winding means, and a third capacitor shunting the second inductance element and the output impedance element.

7. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, one of said winding means having at least two opposed operating windings, a first circuit including a first capacitor connected in closed circuit relation with the second winding means, a second circuit including a second capacitor, a second inductance element and an output impedance element connected in series with each other and in closed circuit relation with the second winding means, and a third capacitor shunting the second inductance element and the output impedance element.

8. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, one of said winding means having at least two opposed operating windings, a first circuit including a first capacitor connected in closed circuit relation with the second winding means, a second circuit including a second capacitor, a second inductance element and an output winding means connected in series with each other and in closed circuit relation with the second winding means, a third capacitor shunting the second inductance element and the output winding means, and a fourth capacitor in series with the first winding means to establish a series ferro-resonant circuit.

9. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, one of said winding means having at least two opposed operating windings, a first circuit including a first capacitor connected in closed circuit relation with the second winding means, a second circuit including a second capacitor, a second inductance element and an output rectifier means connected in series with each other and in closed circuit relation with the second winding means, a third capacitor shunting the second inductance element and the output rectifier means, and a fourth capacitor in series with the first winding means to establish a series ferro-resonant circuit.

10. A magnetic frequency changer adapted to be energized by a suitable source of alternating current and generating a new frequency compris-

ing, in combination, magnetic core means having two saturable magnetic paths substantially equal in magnetic characteristics, first winding means for magnetizing said two saturable magnetic paths to substantially the same flux density, second winding means embracing the two saturable paths, one of said winding means having at least two opposed operating windings, a stabilizing transformer having a first and a second winding portion, a first circuit including a first capacitor and the first winding portion of the stabilizing transformer connected in series and in closed circuit relation with the second winding means, a second circuit including a second capacitor, output rectifier means and the second winding portion of the stabilizing transformer connected in series and in closed circuit relation with the second winding means, a third capacitor shunting the output rectifier means and the second winding portion of the stabilizing transformer, and a fourth capacitor in series with the first winding means to establish a series ferro-resonant circuit.

11. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, one of said winding means having at least two opposed operating windings, a first circuit including a first capacitor connected in closed circuit relation with the second winding means, a second circuit including a second capacitor, a second inductance element and an output impedance element connected in series with each other and in closed circuit relation with the second winding means, a third capacitor shunting the second inductance element and the output impedance element, and output winding means and a capacitor forming a tuned circuit connected in circuit relation with a portion of the first winding means to supply a complex output wave having components including the frequency of the source of alternating current and the new frequency.

12. A magnetic frequency changer adapted to be energized by a suitable source of alternating current and generating a new frequency comprising, in combination, magnetic core means having two saturable magnetic paths substantially equal in magnetic characteristics, first winding means for magnetizing said two saturable magnetic paths to substantially the same flux density, second winding means embracing the two saturable paths, one of said winding means having at least two opposed operating windings, a self-exciting first circuit including a capacitor connected to the second winding means to receive energy therefrom and establishing a leading current of a harmonic of the source to flow through the second winding means to self-excite and bias the magnetic core means for generating the new frequency, a second circuit including a second capacitor, a second inductance element and an output impedance element connected in series with each other and in closed circuit relation with the second winding means, and a third capacitor shunting the second inductance element and the output impedance element.

13. A magnetic frequency changer adapted to be energized by a suitable source of alternating current and generating a new frequency com-

prising, in combination, a magnetizable core provided with two magnetic paths having a bridging member in common, first winding means, second winding means, one of said winding means on each of said paths, a first circuit adapted to be connected to the said source and including a condenser and said first and second winding means in series to create alternating fluxes in said two paths which are in opposition in said bridging member, third winding means inductively related with said bridging member, and a self-exciting circuit including a second capacitor connected to the third winding means to receive energy therefrom and establishing a leading current of a harmonic of the source to flow through the third winding means to self-excite and bias the magnetizable core for generating the new frequency.

14. A magnetic frequency changer adapted to be energized by a suitable source of alternating current and generating a new frequency comprising, in combination, a magnetizable core provided with two magnetic paths having a bridging member in common, first winding means, second winding means, one of said winding means on each of said paths, a first circuit adapted to be connected to the said source and including a condenser and said first and second winding means in series to create alternating fluxes in said two paths which are in opposition in said bridging member, third winding means inductively related with said bridging member, a first circuit including a first capacitor connected in closed circuit relation with the third winding means, a second circuit including a second capacitor, a second inductance element and an output impedance element connected in series with each other and in closed circuit relation with the third winding means, and a third capacitor shunting the second inductance element and the output impedance element.

15. A magnetic frequency changer adapted to be energized by a suitable source of alternating current and generating a new frequency comprising, in combination, a magnetizable core provided with two magnetic paths having a bridging member in common, first winding means, second winding means, one of said winding means on each of said paths, a first circuit adapted to be connected to the said source and including a condenser and said first and second winding means in series to create alternating fluxes in said two paths which are in opposition in said bridging member, third winding means inductively related with said bridging member, a first circuit including a first capacitor connected in closed circuit relation with the third winding means, a second circuit including a second capacitor, a second inductance element and an output impedance connected in series with each other and in closed circuit relation with the third winding means, a third capacitor shunting the second inductance element and the output winding, a fourth capacitor in series with the first and second winding means to establish a series ferro-resonant circuit, and an output winding means connected to the output impedance means and receiving energy therefrom.

16. A magnetic frequency changer adapted to be energized by a suitable source of alternating current and generating a new frequency comprising, in combination, a magnetizable core provided with two magnetic paths having a bridging member in common, first winding means, second winding means, one of said winding means on

each of said paths, a first circuit adapted to be connected to the said source and including a condenser and said first and second winding means in series to create alternating fluxes in said two paths which are in opposition in said bridging member, third winding means inductively related with said bridging member, a first circuit including a first capacitor connected in closed circuit relation with the third winding means, a second circuit including a second capacitor, a second inductance element and an output rectifier means connected in series with each other and in closed circuit relation with the third winding means, a third capacitor shunting the second inductance element and the output rectifier means, and a fourth capacitor in series with the first and second winding means to establish a series ferro-resonant circuit.

17. A magnetic frequency changer adapted to be energized by a suitable source of alternating current and generating a new frequency comprising, in combination, a magnetizable core provided with two magnetic paths having a bridging member in common, first winding means, second winding means, one of said winding means on each of said paths, a first circuit adapted to be connected to the said source and including a condenser and said first and second winding means in series to create alternating fluxes in said two paths which are in opposition in said bridging member, third winding means inductively related with said bridging member, a first circuit including a first capacitor connected in closed circuit relation with the third winding means, a second circuit including a second capacitor, a second inductance element and an output impedance element connected in series with each other and in closed circuit relation with the third winding means, a third capacitor shunting the second inductance element and the output impedance element, and output winding means and a capacitor forming a tuned circuit connected in circuit relation with a portion of the first winding means to supply a complex output wave having components including the frequency of the source of alternating current and the new frequency.

18. A magnetic frequency changer adapted to be energized by a suitable source of alternating current and generating a new frequency comprising, in combination, a magnetizable core provided with two magnetic paths having a bridging member in common, first winding means, second winding means, one of said winding means on each of said paths, a first circuit adapted to be connected to the said source and including a condenser and said first and second winding means in series to create alternating fluxes in said two paths which are in opposition in said bridging member, third winding means inductively related with said bridging member, a self-exciting first circuit including a capacitor connected to the third winding means to receive energy therefrom and establishing a leading current of a harmonic of the source to flow through the third winding means to self-excite and bias the magnetizable core means for generating the new frequency, a second circuit including a second capacitor, a second inductance element and an output impedance element connected in series with each other and in closed circuit relation with the third winding means, and a third capacitor shunting the second inductance element and the output impedance element.

19. A frequency changer adapted to be ener-

gized by a suitable source of alternating current, comprising, in combination, a magnetizable core having two saturable magnetic paths with a bridging member in common, first winding means on each of said magnetic paths, said winding means being connected in series to induce opposing fluxes in said bridging member and being a part of a ferro-resonant circuit including said source, second winding means inductively related to the said bridging member, a plurality of self exciting circuits electrically connected to the second winding means, one of

said self exciting circuits including a capacitor connected in closed circuit with the second winding means and another of said plurality of self exciting circuits including a stabilizing transformer and a full wave rectifier connected in series with each other and in closed circuit relation with the second winding means, a first output circuit coupled to one of said first winding means, and a second output circuit energized from said rectifier.
